UNITED STATES PATENT OFFICE.

BENJAMIN B. MITCHELL, OF BUFFALO, NEW YORK.

BED-BOTTOM.

SPECIFICATION forming part of Letters Patent No. 328,241, dated October 13, 1881.

Application filed March 10, 1885. Serial No. 158,361. (No model.)

To all whom it may concern:

Be it known that I, BENJAMIN B. MITCHELL, of the city of Buffalo, in the county of Erie and State of New York, have invented new and useful Improvements in Bed-Bottoms, of which the following is a specification.

This invention relates to an improvement in that class of folding bed-bottoms which are composed of two spring-supporting frames connected by flexible bars which permit the frames to be folded against or upon each other with the springs attached to the two frames resting against each other. In such bed-bottoms of ordinary construction the length of the flexible connecting-bars is limited by the distances at which the rows of springs are arranged apart, whereby the flexible connecting-bars are necessarily made so short that the springs of the two frames will interfere with each other in folding the bottom, thereby pressing the springs out of shape.

The object of my invention is to remedy this difficulty by connecting the two frames by extensible connections, which are capable of being lengthened in folding the bottom and shortened in unfolding it.

Another object of my invention is to improve the construction of the springs and supporting-frames.

My invention consists to these ends of the improvements which will be hereinafter fully set forth, and pointed out in the claims.

In the accompanying drawings, Figure 1 is a top plan view of my improved bed-bottom with the springs shown in dotted lines. Fig. 2 is a cross-section of the same, on an enlarged scale, showing the bed-bottom unfolded. Fig. 3 is a similar view showing the bed-bottom folded. Fig. 4 is a longitudinal section of the clamp applied to the extensible connecting-bars. Fig. 5 is a top plan view of the same. Fig. 6 is a side view of one of the sway-braces. Fig. 7 is a side elevation of one of the springs. Fig. 8 is a top plan view thereof.

Like letters of reference refer to like parts in the several figures.

A A' represent the spring-supporting frames, each composed of longitudinal bars *a* and cross-bars *a'* rigidly secured together.

A² represents the springs secured with their lower contracted ends to the longitudinal bars

a. The latter are arranged below the cross-pieces *a'*, so that the pressure applied to the springs is directly applied to the longitudinal bars *a* which rest on the slats of the bed-frame, 55 thereby preventing the bars *a* from becoming bent by this pressure, which occurs when these bars are arranged above the cross-pieces *a'*.

b represents the flexible connecting bars secured to the frames A in line with the cross-bars *a'*, and B represents clamps secured to the frames A' for securing the bars *b* thereto. The clamps B consist each of a frame, *c*, secured to the bar *a'*, and a clamping cam or eccentric, *d*, provided with a hand-lever, D. 65 The flexible bar *b* rests on the frame *c* between the side pieces thereof, and passes underneath the clamping-cam *d*, so that upon lowering the lever D the bar *b* is firmly clamped in the frame *c* by the cam *d*, while upon raising the 70 lever D the bar *b* is free to slide on the frame *c*.

e represents a shoulder or stop formed on the end of each bar *b* to prevent the entire separation of the frames A A', and *f* is a shoulder or stop secured to each bar *b* to arrest the 75 closing movement of the frames, when the latter have reached their proper relative position in unfolding the bed-bottom.

When it is desired to fold the bed-bottom, the clamps B are released and the frames A 80 A' separated as far as the sliding bars *b* will permit, which movement is limited by the stops *e*. In this manner the connecting-bars between the frames A A' are lengthened before folding the frames A A' upon each other, 85 and the increased length of the connecting-bars so obtained permits the rows of springs to fold against each other, as represented in Fig. 3, with each row in its proper position without being crowded or deflected by the 90 other springs. Upon unfolding the bed-bottom the bars *b* slide in the clamps B until the stops *f* on the bars *b* strike against the clamps, whereby the connections are shortened so as to bring the frames A A' into their proper relative position. In this position of the frames the bars *b* are secured by the clamps B, whereby both frames are rigidly connected. The frames *c* of the clamps are preferably provided with rollers *g* to facilitate the movements of 95 the bars *b* in the frames *c*.

i represents stiffening-bars secured length-

wise to the upper ends of the springs in the outermost row on each of the frames A A'.

5 I represents bent or C-shaped sway-braces secured with their lower ends to the longitudinal bars *a* of the frames A A' and with their upper ends to the bars *i*, thereby steadyng the springs against lateral vibrations.

*a*² represents a longitudinal bar provided with a row of springs and applied to the connecting-bars *b* when an odd number of rows of springs is used. The bar *a*² is connected with the bars *b* by staples *h* in which the bars *b* slide, and the bar *a*² is steadied by diagonal chains *h'* extending from said bar to the adjacent springs on the frames A A'.

j represents an eye formed in the top coil of each spring A at its junction with the next lower coil and depressed below the upper surface of the top coil.

20 *k* represents a hook formed at the end of the top coil and depressed below the latter to engage in the eye *j*, whereby the top coil is made horizontal over almost its entire length, forming a large and firm support for the bedding placed on the bed-bottom.

I am aware that it is not new to connect the slats by flexible bars which are attached to the slats by sliding connections and clamps which permit the bed-bottom to be collapsed by sliding the slats against each other upon releasing the clamps of the connecting-bars, or to be rolled by bending all of the connecting-bars; and I do not claim such construction.

I claim as my invention—

35 1. The combination, with two frames, A A', each composed of slats *a*' and cross-bars *a*'', rigidly secured together and provided with springs A², of flexible connecting-bars *b*, secured to one frame and attached to the other frame by sliding connections, whereby the

connecting-bars can be lengthened for folding the frames with the ends of the springs resting against each other, substantially as set forth.

2. The combination, with two frames, A A', each composed of slats *a* and cross-bars *a*', rigidly secured together and provided with springs A², of flexible connecting-bars *b*, 45 secured to one frame and sliding in attachments on the other frame, and clamps whereby the sliding ends of the connecting-bars are secured when adjusted, substantially as set forth.

3. The combination, with two frames, A A', each composed of slats *a* and cross-bars *a*', rigidly secured together and provided with springs A², of flexible connecting-bars *b*, 50 provided with stops *e* and *f*, and having fixed connections with one frame and sliding connections with the other frame, and the clamps B, whereby the sliding ends of the connecting-bars are secured, substantially as set forth.

25 4. The combination, with the spring-supporting frames A A', of the flexible bars *b* and the clamps B, composed of frames *c*, cams *d*, levers *D*, and rollers *g*, substantially as set forth.

5. The combination, with the frames A A', each composed of slats *a* and cross-bars *a*', rigidly secured together and provided with springs A², of the flexible connecting-bars *b*, secured to one frame and attached to the other frame by sliding connections, a longitudinal bar, *a*², connecting the flexible bars *b* between the frames A A', and springs secured to the bars *b*, which springs assume a horizontal position when the frames A A' are folded upon each other, substantially as set forth.

65 BENJAMIN B. MITCHELL.
